UNITED STATES PATENT OFFICE.

JOSEPH D. NAGEL, JR., OF NEW YORK, N. Y.

MARKING-TAG.

1,383,417.

Specification of Letters Patent.

Patented July 5, 1921.

Application filed May 13, 1920. Serial No. 381,154.

To all whom it may concern:

Be it known that I, JOSEPH D. NAGEL, Jr., a citizen of the United States of America, residing at New York, in the county of New York and State of New York, have invented certain new and useful Improvements in Marking-Tags, of which the following is a specification.

My invention relates to a marking tag, for use on cloth or other fabric, and articles made from such fabrics, and has for its purpose to afford an economical, safe and readily attachable construction.

A more particular object of the invention is to afford a tag which includes attaching pins, and can be secured to a piece of goods without engaging the points of the pins, thus avoiding pricking one's fingers as with the conventional types of tag.

Another object of the invention is to provide a simple device, requiring only a single piece of wire and a single piece of paper or cardboard, and which can, therefore, be manufactured at low cost.

A further purpose of the improvement is to arrange the parts so that the tag can be readily attached to an article or piece of cloth with only one hand, and by manipulating or bending the wire at its central part, or at some portion between its ends, as distinguished from engaging the points of the pins.

Still an additional object is to accomplish the necessary bending of the wire by folding over one portion of the tag.

Other purposes and advantages of the invention will appear from the following detailed description, in conjunction with the accompanying drawing, the novel features of the invention being pointed out in the claims at the end of the specification.

Referring to the drawing:

Figure 1 is a front elevation of a tag constructed in accordance with a preferred embodiment of my invention, and illustrating the pins in normal position, or before attachment;

Fig. 2 is a rear elevation of the same;

Fig. 3 is a front elevation showing the tag attached to a piece of fabric;

Fig. 4 is a rear elevation of the same;

Fig. 5 is an edge view of Fig. 2, and

Fig. 6 is an edge view of Fig. 4.

The purposes of the invention may be car-

ried out in quite a number of different ways, 55 and accomplished by various practical constructions, and the disclosure of this application is intended merely, by way of example, to illustrate the fundamental characteristics of the improvement.

In the drawing, the tag, which is formed of paper or thin cardboard, comprises a body portion A and an extension or tab B, which is adapted to be folded on the body A along the folding line *a* between the body portion 65 and extension. The necessary indicia which the tag is intended to carry will be provided at its lower part, so that when the extension B is folded over upon the body portion, it will occupy the upper part of the tag and 70 not interfere with the markings on the lower part.

The extension or tab B is not indispensable to a practical working out of the invention, since it might be omitted while still 75 retaining the advantages of the attaching devices about to be described, but it affords a very simple and desirable method of bending the wire and separating the points of the pins.

The attaching devices comprehend a pair of pins, one of which is adapted to be moved with reference to the other, preferably but not necessarily when the tag extension is folded upon the body portion, and to this 85 end I employ a single, integral piece of wire, the ends of which comprise pins C and C' which normally, or before attachment to the cloth, occupy a parallel relation, as shown in Figs. 1 and 2, one of said pins being supported on the body of the tag and the other on the extension. The wire piece also includes a central or connecting portion between the pins C and C', which latter are joined to the central portion at a point coincident with the folding line *a*, the pins extending in a general diagonal direction across the body portion of the tag, and inclined with reference to the wire connecting portion. The central or connecting portion 100 of the wire extends across the tag to the opposite ends thereof, thence through and across the opposite or front side of the tag. Upon the front, the wire includes a bent portion *b* of substantially V-shape, with the base 105 or point of the V coincident with the folding line *a*. The central or connecting portion is manipulated or bent, to actuate the pin C

so as to separate it from pin C' as shown in Fig. 4.

In attaching the tag, it is taken in one hand and the pins pushed through the fabric, as far as they will go. Holding the tag against the fabric in this position, the extension or tab B is engaged by the thumb and bent back upon the body of the tag. This causes a bending of the wire at the base of 10 the V-shaped portion b, superposing one leg of the V upon the other, and at the same time swinging the corresponding pin about the folding line a until it occupies a diverging position with relation to the other pin, 15 as shown in Figs. 4 and 6. With the pins in this relative position, the tag cannot be accidentally displaced from the cloth, and to remove it, it is only necessary to bend the tab B and the wire back to the initial position. 20 One of the important advantages of the invention is that the pins can be separated without bringing one's fingers in contact with the points, but merely by engaging and bending the tab or extension B, or by otherwise manipulating the central part of the 25 wire to effect movement of one of the pins. It will be obvious that the structure shown may be modified without departing from the fundamental features of the invention, 30 and it is the purpose of this application to cover any modifications or changes as may come within the scope of the improvement, or as defined by the following claims.

I claim:

35 1. A marking tag comprising two portions adapted to be folded, one upon the other, and a pin extending from each of said portions, the pins being movable, one away from the other, when said portions are 40 folded.

2. A marking tag comprising two portions adapted to be folded, one upon the other, attaching devices comprising a pair of pins, and means whereby the pins are 45 moved into diverging relationship by folding over a portion of the tag.

3. A marking tag comprising two portions adapted to be folded, one upon the other, attaching devices comprising a pair 50 of pins, and a wire connecting portion between the pins adapted to be bent when the tag is folded and thereby to move the pins into diverging relationship.

4. A marking tag comprising two portions 55 adapted to be folded, one upon the other, attaching devices comprising a pair of pins forming the ends of a piece of wire, the pins being moved into diverging relationship by folding the tag and thereby manipulating the central portion of said wire.

5. A marking tag comprising two portions one adapted to be folded upon the other, attaching devices comprising a pair of pins 60 normally parallel to each other, and a wire connecting portion between the pins, said

connecting portion being bent when the tag is folded to cause said pins to assume a diverging relationship.

6. A marking tag comprising a body portion and an extension foldable on the body portion, and a pair of pins supported on the body portion and extension respectively and normally occupying a parallel position, said pins being brought into diverging relationship by folding said extension upon the 75 body portion.

7. A marking tag comprising a body portion and an extension foldable thereon, and attaching devices consisting of a piece of wire, the ends of which comprise pins located upon one side of the tag while the central portion extends through the tag and across the opposite side thereof, and is foldable with said extension in order to separate 80 the points of the pins.

8. A marking tag comprising a body portion and an extension foldable thereon, and attaching devices comprising a piece of wire, the ends of which comprise pins located on one side of the tag and normally parallel to 90 each other, and a central or connecting portion extending through the tag and across the opposite side thereof, said central portion acting to separate the points of the pins when folded with the extension upon the 95 body portion of the tag.

9. A marking tag comprising a body portion and an extension foldable thereon along a line between the body portion and extension, and attaching devices comprising a 100 piece of wire, the ends of which comprise pins located on one side of the tag and normally in parallel relationship, and a central or connecting portion between the pins which extends through the tag and across 105 the opposite side thereof, said connecting portion being foldable along with the extension on said folding line, and thereby serving to move one of the pins into diverging relationship with the other.

10. A marking tag comprising a body portion and an extension foldable thereon along a line between the extension and the body portion, and attaching devices comprising a piece of wire, the ends of which comprise pins located on one side of the tag and normally in parallel relationship, and a central or connecting portion between the pins, said connecting portion extending through the tag and including, on the side opposite to 115 the pins, a V-shaped portion, the point of which coincides with said folding line between the extension and the body portion of the tag, whereby, when the extension is folded, said V-shaped portion of the wire is bent upon itself at the center, causing one of said pins to be moved into diverging relationship with the other.

11. A marking tag comprising a body portion and an extension foldable thereon along 120

a line between the body portion and extension, and attaching devices comprising a piece of wire, the ends of which comprise pins normally in parallel relationship with each other on one side of the tag, and a central or connecting portion between the pins which extends through the tag and across the opposite side thereof and includes, upon said opposite side, a V-shaped portion, the point of which coincides with said folding line between the extension and the body portion of the tag, said pins being normally in-

clined with reference to the connecting portion and joined thereto at a point coincident with said folding line. 15

12. A marking tag comprising two portions, one of which is foldable upon the other, and a pair of pins, one supported on each of said portions, said pins being moved into diverging relationship by folding one portion upon the other. 20

In witness whereof, I have hereunto signed my name.

JOSEPH DARWIN NAGEL, JR.
